UNITED STATES PATENT OFFICE.

FREDERICK J. SEYMOUR, OF CLEVELAND, OHIO, ASSIGNOR TO THE BROWN'S
SEAMLESS METAL COMPANY, OF JERSEY CITY, NEW JERSEY.

METHOD OF MAKING GUNS AND ORDNANCE.

SPECIFICATION forming part of Letters Patent No. 376,168, dated January 10, 1888.

Application filed June 15, 1885. Renewed June 17, 1887. Serial No. 241,612. (No model.)

To all whom it may concern:

Be it known that I, FREDERICK J. SEYMOUR, of the city of Cleveland, in the county of Cuyahoga and State of Ohio, have invented a new and useful Improvement in the Method of Making Guns or Ordnance, of which the following is a specification.

This invention relates to the manufacture of ordnance and cannon by first producing a number of drawn tubes or shells, which are preferably of steel, and in then securing them one within another to form a cannon or piece of ordnance, whereby a very strong gun will be produced.

15 In carrying out my invention I first produce a number of seamless drawn metal tubes or cylindric shells which are of such relative size that they may be slipped easily one within another, and which have their surfaces finished in the operation of drawing, and I afterward contract the several tubes or shells one upon another, so as to permanently connect them, each tube or shell forming the mandrel upon which the next outermost tube or shell 25 is contracted and secured.

In carrying out my invention the contraction of the metal tubes or shells may be effected by an operation analogous to spinning, or by forcing the tubes through a die of suitable size 30 by a proper mandrel, or I may secure the tubes one upon another by means of a machine similar to that shown in my application for Letters Patent, Serial No. 166,833, filed May 27, 1885.

In the accompanying drawings, Figure 1 represents in sectional view two tubes or shells arranged one within another and such parts of a machine similar to that described in my aforesaid application as are necessary to clearly illustrate the invention; and Fig. 2 represents 40 a sectional view of three tubes secured one upon another and forming a gun, which only requires the addition of a trunnion-band to complete it.

Similar letters of reference designate corresponding parts in both figures.

The gun represented in Fig. 2 is composed of three separate tubes or shells, *a b c*, which are made of iron or of a mild steel, or which may, in the case of brass ordnance, be made of 50 drawn brass. These tubes or cylindric shells

are formed from disks or circular plates of metal of a thickness much greater than the shells or tubes are to have when finished. The method of forming them may be that commonly practiced in making drawn seamless hollow tubes of metal, and I prefer to make them by the method described in Letters Patent No. 316,600, granted April 28, 1885, to William Henry Brown, and which consists in subjecting the metal to the principal operations of drawing or folding in a heated state and to the later operations of drawing in a cold state. According to this method the disks or circular blanks of metal are heated and first dished up by machinery commonly used for such operations. They are again heated and pushed through dies by means of cylindric plungers or mandrels, and this operation, commonly used in drawing hollow cylinders, is repeated as many times as may be necessary for each tube 65 or shell, using smaller and smaller plungers or mandrels and corresponding dies in the successive repetitions of the operations until the tube or shell is of the requisite caliber externally and internally. The last few passes of 70 the tube or shell on the mandrel through the die are made with the metal in a cold state, in order to condense or harden the metal and increase its tensile strength, and that in the case of the innermost tube, *a*, the interior of said 75 tube may be smoothed and hard-finished to constitute the bore of the gun without further finish.

Of the several tubes *a b c* required to form a gun or cannon the innermost one is of the full 80 length of barrel, and the outer ones may be successively shorter, so that all their several thicknesses are combined only in and near the breech, where the greatest strength is required, and the walls of the barrel of the gun are gradually thinner toward the muzzle, where least 85 strength is required.

The several tubes or shells are made of such size that when complete and finished by the operations of drawing they may be slipped 90 one inside another.

In Fig. 1 I have represented a part of the apparatus whereby the tubes may be contracted one on another. In the figure, *B* designates a mandrel or spindle, which may be supported 95

in suitable bearings, (not shown,) and receives 5
rotary motion by bevel-wheels B' B^2 from a
driving-shaft, B^3 . I have also represented a
binding-screw, C , which is concentric with the
mandrel and has at its lower end a rotary foot-
piece or steadiment, C' , by which the one or
more tubes or shells may be clamped upon the
mandrel B , so as to rotate therewith.

H designates a slide or a portion of the carriage 10
to which is fitted in suitable bearings, g , a
spindle, h , provided at its lower end with a
spinning tool or disk, h' . By means of mech-
anism such as described in my aforesaid ap- 15
plication for Letters Patent the spinning tool
or disk is traversed from top to bottom of the
tube b , at the same time being pressed forcibly
against the outer circumference thereof, and 20
as the mandrel, with the tubes upon it, rotates
the spinning tool or disk h' contracts the outer
tube or shell, b , upon the inner shell, a , and
permanently secures it thereon. Consequently 25
the two tubes or shells which were previously
slipped one upon another will be permanently
connected, the inner tube, a , constituting the
mandrel upon which the next outer tube, b , is 30
contracted or reduced. This operation is to
be repeated one or more times with each tube
 b as may be found necessary, and in this way
the tubes or shells are contracted and caused 35
to bind or grasp firmly upon the tube or shell
which is next innermost. After the required
number of tubes or shells to form a gun of the
necessary strength have been secured one upon
another, as described, a trunnion-band may be
secured upon the shells by shrinking or other-
wise to complete the gun.

I am aware that it is not new to produce a
vessel made of layers or thicknesses of two or
more metals by first spinning one metal to the

desired shape and then spinning a disk of an- 40
other metal to change its form, so that it will
closely hug the exterior of the vessel. Such a
method of making composite vessels is de-
scribed in the patent granted Philip P. Meyer,
January 1, 1867, and numbered 60,770. My 45
process or method differs from that described
in Meyer's patent in that I first produce all
the component parts of my gun in the form of
drawn cylinders each having its internal di- 50
ameter but slightly greater than the external
diameter of the cylinder which it is to receive.
Before the process of contracting them one
upon another is performed they are all pro-
duced in the form of cylinders, and all have
the close texture and the extremely hard sur- 55
faces which can be obtained only by drawing,
and cannot be obtained by a spinning opera-
tion whereby the metal is changed in form from
a disk to a cylinder.

What I claim as my invention, and desire to 60
secure by Letters Patent, is—

The improvement in the method of making 65
cannon or ordnance, consisting in producing
a number of cylindric drawn tubes or shells
each having its interior and exterior surfaces
finished in the operation of drawing, and the
several tubes or shells being of such relative
diameters that they may be slipped one upon 70
another, and in afterward contracting the sev-
eral tubes or shells by successive operations
one upon another, each tube or shell forming
the mandrel upon which the tube or shell next
outermost is contracted, substantially as herein
described.

FREDK. J. SEYMOUR.
